(57) **CLAIM**

The ornamental design for an animal paw handheld showerhead, as shown and described.

DESCRIPTION

FIG. 1 is a top, left perspective view of the handheld showerhead of my design;

FIG. 2 is a top, left perspective view thereof with a connection to a flexible hose;

FIG. 3 is a front elevation view of the handheld showerhead;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines shown represent unclaimed subject matter and form no part of the claimed design. Specifically, the flexible hose shown in FIG. 1 is for illustrative purposes and forms no part of the claimed design.
